CLAIM

The ornamental design for a wet towel bucket, as shown and described.

DESCRIPTION

FIG. 1 is a front-top-right-side elevational view of a wet towel bucket according to a first embodiment;
FIG. 2 is a left-side view of the first embodiment;
FIG. 3 is a right-side view of the first embodiment;
FIG. 4 is a front view of the first embodiment;
FIG. 5 is a rear view of the first embodiment;
FIG. 6 is a top view of the first embodiment; and
FIG. 7 is a bottom view of the first embodiment.
FIG. 8 is a front-top-right-side elevational view of a wet towel bucket according a second embodiment;
FIG. 9 is a left-side view of the second embodiment;
FIG. 10 is a right-side view of the second embodiment;
FIG. 11 is a front view of the second embodiment;
FIG. 12 is a rear view of the second embodiment;
FIG. 13 is a top view of the second embodiment; and,
FIG. 14 is a bottom view of the second embodiment.
The broken lines in FIG. 7 depict portions of the wet towel bucket that form no part of the claimed design. The faded out portions and broken lines in FIG. 14 depict portions of the wet towel bucket that form no part of the claimed design.
